UNITED STATES PATENT OFFICE.

FRITZ DÜRR, OF SCHLACHTENSEE, GERMANY.

DOUBLE-CYLINDER HYDROCARBON-MOTOR.

SPECIFICATION forming part of Letters Patent No. 699,503, dated May 6, 1902.

Application filed July 5, 1900. Serial No. 22,584. (No model.)

To all whom it may concern:

Be it known that I, FRITZ DÜRR, a subject of the Emperor of Germany, residing at Schlachtensee, in the Empire of Germany, 5 have invented certain new and useful Improvements in Double-Cylinder Hydrocarbon-Motors, of which the following is a full, clear, and exact specification.

The present invention relates to an improvement in hydrocarbon-motors; and the same consists in journaling the driving-shaft between the two cylinders. In each cylinder is contained two pistons moving in opposite directions. Each two pistons are attached to 15 the double crank-shaft by connecting-rods, so that they counterbalance each other. In each working cylinder is arranged a common working space, and in each cylinder the operation is accomplished in four-cycle form.

20 The working periods in the two cylinders are arranged as follows: It occurs that in the one cylinder explosion, exhaust, admission, compression; in the other cylinder admission, compression, explosion, exhaust. In consequence of this distribution of work a universal turning effect is exerted on the driving-shaft.

Figure 1 shows such a hydrocarbon-motor with vertically-arranged working cylinders in 30 cross-section; but the cylinders may be arranged horizontally. Fig. 2 is a vertical section on line II II of Fig. 1, and Fig. 3 is a vertical section on line III III of Fig. 1 viewed in the direction of the arrow 5.

35 The working cylinders 6 and 7 are connected by a foundation-plate 8. On the latter are arranged the journal-boxes 9 and 10, in which the double cranked driving-shaft 11 is journaled. In each cylinder are placed two 40 pistons 12 and 13, running in opposite directions. Each piston is connected by a connecting-rod 14 with a swinging double lever 15 16 17 18. Each double lever is connected to a pivoted arm 19 in the journal *i* on the 45 cylinder. The two ends of the double levers 15 and 16 are turned toward each other and movably coupled together by a bolt 20. The levers 17 and 18 are likewise secured. To each of these bolts is attached a connecting- 50 rod 21 22, which are connected with the double crank-shaft. Two of the pistons 12 and 13 have a common working space 24 and 25,

and from the latter lead a port 26 to the valve-chests 27 and 28, arranged on the outside of the cylinder. In each valve-chest are contained two valves 30 and 31, closed by springs 29, of which the first is the suction-valve, the latter acting as an exhaust-valve. The suction-valve opens automatically, while the exhaust-valve is operated at the proper time by 60 valve-gearing. For this purpose two gear-wheels 32 and 33 are arranged on the driving-shaft, and two gear-wheels 34 and 36 are placed on a counter-shaft in the journal 9. The wheel 32 is secured to the driving-shaft, 65 while the wheel 35 is loose. The wheels 33 36 are mounted so as to move together. The proportion of these four wheels is such that while the wheel 32 makes two revolutions the wheel 35 makes one—*i. e.*, two to one. 70

The wheel 35 is firmly secured to a cam-plate 37, whose cam-finger alternately exerts its influence on pivoted levers 39 40, properly journaled on both cylinders. Each of these levers engages with the valve-stems 31 of the valves. 75

When an explosion occurs in the space 24, the driving-shaft turns one hundred and eighty degrees, while the wheel 35, with the cam-plate 37, has only made ninety degrees. The cam 38 then acts on the lever 39, and the 80 exhaust-valve 31 is opened, so that the burned gases in the cylinder can escape to the open air.

During the explosion in the space 24 the space 25 is filled with fresh-gas mixture as 85 the valve 30 in the valve-chest opened automatically, while at the same time in the space 25 a vacuum has been produced by the pistons moving apart. The springs of the valves 31 must be self-acting and stronger than those 90 of the valves 30 to prevent the admission through the valves 31 by self-action of the valves. If the explosion has occurred in the space 25, then the cam 38 will have come in contact with the valve-stem in the chest of 95 the valve 31, so that the latter will open and the burned gases from the working space 25 escape.

Having thus described my invention, what I claim as new, and desire to secure by Letters Patent, is—

1. A hydrocarbon-motor comprising two parallel cylinders, two oppositely-moving pistons in each cylinder, a driving-shaft jour-

naled between said cylinders, a crank mounted on the driving-shaft, and connections between the pistons and crank-shaft allowing the pistons in both cylinders to move apart and to 5 move together simultaneously.

2. A hydrocarbon - motor comprising two parallel cylinders, two oppositely-moving pistons in each cylinder, a driving-shaft journaled between said cylinders, a crank mounted 10 on the driving-shaft, and connections between the crank and the pistons comprising a swinging lever for each piston, a connecting-rod between the crank-shaft and each two adjacent swinging levers.

15 3. A hydrocarbon - motor comprising two

parallel adjacent cylinders each having two oppositely-moving pistons, an inlet-valve and an exhaust-valve, a crank-shaft mounted between the two cylinders and connected with the aforesaid pistons, a cam-wheel rotatable 20 upon the crank-shaft, mechanism driving the cam-wheel, and a swinging arm on each of said cylinders actuated by the said cam-wheel and operating the exhaust-valves.

In witness whereof I have hereunto set my 25 hand in presence of two witnesses.

FRITZ DÜRR.
